DESIGN FOR AN ARTIFICIAL TOOTH

John B. La Due and Jacob A. Saffir, Chicago, Ill.

Application December 23, 1938, Serial No. 81,963

Term of patent 14 years

To all whom it may concern:

Be it known that we, John B. La Due and Jacob A. Saffir, citizens of the United States and residing at Chicago, in the county of Cook and State of Illinois, have invented a new, original, and ornamental Design for an Artificial Tooth, of which the following is a specification, reference being had to the accompanying drawing, forming a part thereof.

In the drawing:

Figure 1 is a top plan view of an artificial tooth embodying our novel design;

Figure 2 is a side view of the tooth; and
Figure 3 is a vertical sectional view of the tooth taken on its major axis as identified by the line 3—3 of Figure 1.

The dominant features of our design reside in the portions shown in full lines.

We claim:

The ornamental design for an artificial tooth, as shown and described.

JOHN B. LA DUE.
JACOB A. SAFFIR.
